UNITED STATES PATENT OFFICE

125,945

DESIGN FOR A SLEEPING DOG TOY

Charlotte Steiner, New York, N. Y.

Application June 7, 1940, Serial No. 92,869

Term of patent 3½ years

To all whom it may concern:

Be it known that I, Charlotte Steiner, a citizen of Germany (Austria), residing at New York, in the county of New York and State of New York, have invented a new, original, and ornamental Design for a Sleeping Dog Toy, of which the following is a specification, reference being had to the accompanying drawing, forming part thereof.

The figure is a side elevation of a sleeping dog toy showing my new design.

The article is of general pillow form and the opposite side is of substantially the same appearance as the side shown.

I claim:

The ornamental design for a sleeping dog toy, as shown and described.

CHARLOTTE STEINER.
